UNITED STATES PATENT OFFICE

ERNEST O. FREDERICKS, OF NEW YORK, N. Y.

METHOD AND MEANS FOR SECTIONAL TREATMENT IN PERMANENT WAVING OF HAIR

Application filed October 27, 1927. Serial No. 229,142.

This invention relates to tubular containers of improved construction for use in connection with permanent waving of hair and to methods of using the same.

5 It is an object of the invention to provide a device which is adapted for the treatment of certain sections only of the hair in permanent waving whereby rewaving or waving in certain styles is facilitated.

10 Another object is to provide a device which, at the election of the operator, can be used to wave either the newly-grown hair near the roots alone, or the end portions of the hair alone, or both, or the intermediate 15 portions alone.

Other objects of the invention will in part be obvious and will in part appear herein-after.

The invention accordingly comprises an 20 article of manufacture possessing the features, properties and the relation of elements which will be exemplified in the article hereinafter described, and the scope of the application of which will be indicated in the 25 claims.

For a fuller understanding of the nature and objects of the invention reference should be had to the following detailed description taken in connection with the accompanying drawings, in which:

Figure 1 is a perspective view of one form of the device;

Figs. 2 and 3 are perspective views of other embodiments of the invention;

35 Fig. 4 is a partly sectional view taken along the line 4—4 of Fig. 3; and

Fig. 5 is a side elevational view of the form of device shown in Fig. 1 applied to a tress of hair.

40 Referring first to Figs. 1 and 5 of the drawings, the present device comprises generally a tubular container 10 open at both ends as at 11 and which is adapted to be positioned over a tress of hair 12, wound on a mandrel 12', and to have a tubular heater, as shown in dotted lines at 13, positioned thereover. As is usual, the heater generates the heat for effecting the permanent waving of a tress of hair, and the end of the tube next the scalp 45 is crimped as at 14 and is held together as by

a clip 15, which prevents the steam, gases, vapors or heat within the tube from scalding or burning the scalp of the person being treated. As indicative of the action of the device, it will be observed that as shown in Fig. 5 the device is adapted to retain gases in the front portion of the tube and permit the gases to issue from other perforations.

55 In order that the heat from the heater 14 may be transmitted to the tress of hair, the tube 10 preferably is constructed of a material which transmits heat readily, such as, for example, metal, metal foil, or the like. It is to be understood, however, that any suitable substance may be used, such as, for example, paper or cloth, which, if desired, may be suitably impregnated to decrease the danger of fire. Also, as is shown in Figs. 2, 3 and 4, the device, if desired, may be composed of one or more layers of materials in addition to the outside layer. For example, in Fig. 2, an embodiment is shown in which, inside of the tube 10'—which in this case is of metallic foil—is a tube 16 of thin paper, cloth or the like, which may have the function of being normally impervious to gases or the like, or may discolor at critical temperatures. Also, as is shown in Figs. 3 and 4, a hair-treating composition 17 may be situated within the external tube 10 or between the external tube 70 and the layer 16. Such hair-treating composition may be of any desired composition and may, if desired, be placed in the tube either in the form of a thin sachet or by impregnation of a layer of cloth or the like.

75 As will be seen from the drawings, the tube 10, together with any auxiliary layers which may be contained therein, is perforated as at 18. These perforations are for the purpose of allowing the gases, vapors, steam or heat (hereinafter referred to generically as "gases") to escape freely from certain portions of the tress of hair while retaining them around and intimately in contact with a certain other section or sections of the hair. 80 These perforations may be of any number, size, or disposition as long as the functions above referred to are attained, i. e., the tube is to be so constructed that it will retain the gases around those portions of the hair which 85

are to be waved or treated and will freely release the gases around those portions of the hair which are not to be treated. In this manner wide variation in the type of waving can be attained by the operator. In other words, the operator can at will wave either that portion of the hair near the roots, the end portions of the hair or both, or an intermediate portion of the hair alone.

10. To accomplish the waving of either of the end portions, the form of device shown in Fig. 1 is used, in which the perforations 18 are at one end of the tube, it being understood that the imperforate end of the tube is to be 75 positioned over that portion of the hair which it is desired to wave; or waving both ends, the form shown in Fig. 2 is used, in which the perforations are in the intermediate portions only, and for waving the intermediate portions only, the form shown in Fig. 3 is used, in which the perforations are at each end. In the former case, it may be found desirable to clip the tube at both ends in order to insure the proper retention of the "gases".
15. Since certain changes may be made in the above article, and different embodiments of the invention could be made, without departing from the scope thereof, it is intended that all matter contained in the above description 80 or shown in the accompanying drawings shall be interpreted as illustrative and not in a limiting sense.

It is also to be understood that the following claims are intended to cover all of the 85 generic and specific features of the invention herein described and all statements of the scope of the invention which as a matter of language might be said to fall therebetween.

Having described my invention, what I 90 claim as new and desire to secure by Letters Patent is:

1. As an article of manufacture, a container for enclosing a tress of hair during the heating operation of a permanent-waving 95 process comprising a gas-impervious tube adapted to be inserted in a heater and being perforated circumferentially in a manner such as to form a plurality of bands, certain ones of said plurality being separated from 100 each other by the remainder of said plurality, certain of said bands being gas-pervious and certain other of said bands being gas-impervious.

2. As an article of manufacture, a container for enclosing a tress of hair during the heating operation of a permanent-waving 105 process comprising a gas-impervious tube of a material adapted readily to transmit heat, said tube being adapted to be inserted into a heater and being perforated circumferentially in a manner such as to form a plurality of bands, certain of said bands being gas-pervious and certain other of said bands being gas-impervious.

3. As an article of manufacture, a contain-

er for enclosing a tress of hair during the heating operation of a permanent-waving process comprising a metallic tube adapted to be inserted into a heater and being perforated circumferentially in a manner such 70 as to form a plurality of bands, certain of said bands being gas-pervious and certain other of said bands being continuous and gas-impervious.

4. As an article of manufacture, a container for enclosing a tress of hair during the heating operation of a permanent-waving process comprising a tube having an external layer of material adapted readily to transmit 75 heat, and a second layer of material which is impervious to gases, both of said layers being perforated in certain portions to form a relatively wide band of openings for the escape of gases.

5. As an article of manufacture, a container for enclosing a tress of hair during the heating operation of a permanent-waving process comprising a tube having an external layer of material adapted readily to transmit 80 heat, a second layer of material which is impervious to gases, and a hair-treating composition intermediate said layers, both of said layers being perforated in certain portions to form a relatively wide band of openings 85 for the escape of gases.

6. A method of waving hair, which comprises coiling a tress of hair on a mandrel, surrounding the hair with a tube having an external layer of material adapted readily to transmit heat and a second layer of material which is impervious to gases, both of said layers being perforated in certain portions to form a relatively wide head of openings 90 for the escape of gases, and subjecting the hair within the imperforate portion of the tube to the action of heat in the presence of moisture.

7. A method of waving hair, which comprises coiling a tress of hair on a mandrel, surrounding the hair with a tube having an external layer of material adapted readily to transmit heat and a second layer of material which is impervious to gases, both of said layers being perforated in their central portions to form a relatively wide band of openings 95 for the escape of gases, clipping the ends of the tube, and subjecting the hair within the imperforate portion of the tube to the action of heat in the presence of moisture.

8. As an article of manufacture, a container for enclosing a tress of hair during the heating operation of a permanent-waving process comprising a tube having relatively wide perforate and imperforate sections, said tube including a plurality of layers, some of which are constructed of materials impregnated with a hair-treating substance, at least one of said layers being adapted readily to transmit heat.

9. As an article of manufacture, a contain-

- er for enclosing a tress of hair during the heating operation of a permanent-waving process comprising a tube having relatively wide perforate and imperforate sections, said tube including a layer adapted readily to transmit heat, and a layer of gas-impervious material within said first-mentioned layer in registry with the imperforate portion thereof.
- 10 10. As an article of manufacture, a container for enclosing a tress of hair during the heating operation of a permanent waving process, comprising a tube composed of a plurality of layers of gas-impervious materials some of which are constructed of materials impregnated with a hair-treating substance, said layers being in registry throughout a portion of the length of said tube, the outer one of said layers being composed of metal, said tube being formed with a band of perforations through said layers at at least one point of its length.
- 15 11. As an article of manufacture, a container for enclosing a tress of hair during the heating operation of a hair-waving process comprising a laminated tube having at least one layer of a relatively hard material, at least one layer of a relatively soft material, one of said layers being impervious to gases and all layers perforated in certain portions to form a relatively wide band of openings for the escape of gases.
- 20 12. As an article of manufacture, a container for enclosing a tress of hair during the heating operation of a hair-waving process, comprising a laminated tube having one external layer of a relatively hard material, at least one layer of a relatively soft material, one of said layers being impervious to gases, and all layers perforated in certain portions to form a relatively wide band of openings for the escape of gases.
- 25 13. As an article of manufacture, a container for enclosing a tress of hair during the heating operation of a hair-waving process comprising a laminated tube having a plurality of bands, certain ones of said plurality being separated from each other by the remainder of said plurality, certain ones of said bands being gas-pervious, certain other of said bands being gas-impervious, and the laminations being in registry.
- 30 14. As an article of manufacture, a container for enclosing a tress of hair during the heating operation of a hair-waving process comprising a laminated tube, having a plurality of bands, those bands situated at the extremities of said tube being gas-pervious, said gas-pervious bands being separated from each other by a gas-impervious band, and the laminations being in registry.
- 35 15. As an article of manufacture, a container for enclosing a tress of hair during the heating operation of a hair-waving process, comprising a laminated tube having a
- plurality of bands, certain groups of said bands situated near the mid-portion of said tube being gas-pervious, certain bands near the extremities of said tube being gas-impervious, and the laminations being in registry. 70
- 40 16. As an article of manufacture, a container for enclosing a tress of hair during the heating operation of a hair-waving process, comprising a laminated tube having at least one layer of a relatively hard material, at least one layer of a relatively soft material, one of said layers being impervious to gases, having a plurality of bands, certain ones of said plurality being separated from each other by the remainder of said plurality, certain ones of said bands being gas-pervious, certain other of said bands being gas-impervious, and the laminations being in registry. 80
- 45 17. A method of waving hair, which comprises waving a tress of hair upon a mandrel, and surrounding the hair with a laminated tube having at least one layer of a relatively hard material, at least one layer of a relatively soft material, one of said layers being impervious to gases, and all layers perforated in certain portions to form a relatively wide band of openings for the escape of gases. 85
- 50 18. As an article of manufacture, a container for enclosing a tress of hair during the heating operation of a hair-waving process, comprising a laminated tube having a band of perforations situate at an extremity, said band being gas-pervious, said perforations in various layers being in registry. 90
- 55 19. In testimony whereof I affix my signature. 100
